SUPPORT STAND FIXTURE

Walter R. Goodridge, Greenville, R.I., assignor to Mr. Christmas, Inc., New York, N.Y., a corporation of New York

Filed Nov. 22, 1967, Ser. No. 9,498

Term of patent 14 years

(Cl. D54—1)

FIG. 1

FIG. 2

FIG. 1 is a perspective view of a support stand fixture, partially open;

FIG. 2 is a top plan view of FIG. 1;

FIG. 3 is a bottom plan view of FIG. 1; and

FIG. 4 is a side elevational view, closed, and looking into one of the leg-clamping sleeves thereof.

I claim:

The ornamental design for a support stand fixture, as shown and described.
